(57) **CLAIM**

The ornamental design for a protective case for a memory storage device which is connectable to a computer or an MP3 player device, as shown and described.

DESCRIPTION

FIG. 1 is a perspective view of a protective case showing my new design;

FIG. 2 is a side elevational view thereof as seen from the left in FIG. 1, the right side elevational view thereof being a mirror image;

FIG. 3 is a front elevational view thereof as seen from the right in FIG. 2;

FIG. 4 is a top view thereof;

FIG. 5 is a back view thereof; and,

FIG. 6 is a bottom view thereof.

The four circular elements shown in broken lines in FIG. 6 represent portions of the design that form no part of the claim.
